(57) **CLAIM**

The ornamental design for a tub for bathing, as shown and described.

DESCRIPTION

In a preferred embodiment, the nature of this product is as a plumbing fixture in the form of a bathing tub primary useful for washing the human body.

FIG. 1 is a right, top, front perspective view of a tub for bathing embodying my new design;

FIG. 2 is a top plan view thereof;

FIG. 3 is a front elevational view thereof, the rear elevational view thereof being a mirror image of the front elevational view shown;

FIG. 4 is a right side elevational view thereof

FIG. 5 is a left side elevational view thereof;

FIG. 6 is a bottom plan view thereof;

FIG. 7 is a left, top, front perspective view of a tub for bathing according to another embodiment of our new design, the right and left side elevational views thereof being identical to views shown in respective FIGS. 4 and 5;

FIG. 8 is a top plan view thereof;

FIG. 9 is a front elevational view thereof, the rear elevational view thereof being a mirror image of the front elevational view shown; and,

FIG. 10 is a bottom plan view thereof.

The broken line representations of a drain in FIGS. 2-6 and 8-10, and an overflow/control in FIGS. 2, 4, 6 and 8 are for the purpose of illustration only, and form no part of the claimed design.
